UNITED STATES PATENT OFFICE.

LEWIS E. GOULD, OF NASHUA, NEW HAMPSHIRE.

EAVES-TROUGH HANGER.

SPECIFICATION forming part of Letters Patent No. 368,828, dated August 23, 1887.

Application filed May 20, 1884. Serial No. 132,208. (No model.)

To all whom it may concern:

Be it known that I, LEWIS E. GOULD, a citizen of the United States, residing at Nashua, in the county of Hillsborough and State of New Hampshire, have invented new and useful Improvements in Eaves-Trough Hangers, of which the following is a specification.

My invention relates to eaves-trough hangers, and the purpose thereof is to obtain a simple, perfect, and exact adjustment of the supporting-arm vertically and horizontally, and to provide a hanger which may be used upon square, bevel, or "ogee" finish indifferently.

My invention consists in the several novel features of construction and combinations of parts, hereinafter fully set forth, and definitely pointed out in the claims following this specification.

Referring to the drawings forming part of this specification, Figure 1 is a side elevation showing my invention. Fig. 2 is a vertical section in the plane 2 2, Fig. 1.

A in said drawings represents a bracket-arm, which may be cast or otherwise formed of any suitable metal. Its end may be curved upward and provided with a vertical flange, *a*, as shown in Fig. 1, through which the attaching-screws pass. In order to lighten the bracket and cheapen its construction, superfluous metal is removed by forming openings at intervals in its body portion. Throughout the straight portion of the bracket is formed a longitudinal slot, *a'*, and upon the face of the slotted portion, at or near the edge, is cast a projecting rib, *b*, the function of which will be presently described. Upon the opposite face the bracket is cut away to form a shallow channel upon each side of the slot, said channel lying between the projecting edges *c c*.

D represents a rectangular metallic loop having a flat oblong block, *d*, formed upon its rear side. The loop is of such thickness that it will pass through the slot *a'*, the block *d* being adapted to lie in the channel between the edges or ribs *c c*.

E indicates the upright arm, which is cast or otherwise formed with a trough-hook, *E'*, upon its upper end. In the front and rear face of the upright is formed a channel, *E'*, and upon the rear face the vertical ribs or edges, which lie upon each side of said chan-

nel, are serrated, as shown at *e*, Fig. 2. The upright thus formed is inserted within the loop *D*, its serrated edges *e* being next to the bracket *A*, and when it has been adjusted vertically a key, *F*, is placed in the channel *E'* and pushed downward into the loop. This key, being wedge-shaped, forces the upright against the bracket until its toothed edges *e* engage with the rib *b* upon the arm *A*, thereby holding the arm securely in the position to which it is adjusted. By simply raising the key in the channel *E'* the arm *E* may be raised or lowered, and at the same time any required horizontal adjustment may be made by sliding the loop *D* in the slot *a'*.

The upright arm may be lightened by forming openings therein at intervals. The trough-hook *E'*, mounted upon its upper end, has a loop, *e'*, to receive the roll of the trough, and upon the extremity of the opposite arm is a recess, *e'*, covered by a fin of metal, *e*, in which is formed an aperture to receive a fastening device by which the edge of the trough may be held.

The vertical and horizontal adjustment of the trough-hook is represented in Fig. 1 by full and dotted lines.

I claim—

1. In a trough-hanger, the combination, with the slotted horizontal bracket having a projecting rib upon its face, of a vertical arm having serrations engaging with said rib, a loop passing through the slot in the latter and surrounding the upright, and a key inserted between the loop and the upright, substantially as and for the purpose described.

2. The combination, with the slotted bracket, of the upright carrying the trough-hook, and an adjusting-connection moving in the slot of the brackets, with a key engaging said connection and forcing the upright against the horizontal arm, substantially as and for the purpose set forth.

3. The slotted bracket having a feather, *b*, upon one face and channeled upon the opposite face, the upright having serrations *e* upon its rear face and a channel, *E'*, in its front, a loop, *D*, having block *d*, and the wedging-key *F*, combined substantially as and for the purpose described.

4. A trough-support consisting of two parts,

one having a slot and a projection or rib on one side of the slot, and the other part having projections engaging with the projection or rib on the first part, said parts being held in connection by a third element which engages with one part, passes through the slot in the other, and is held by the action of a key or wedge, substantially as specified.

In testimony whereof I have hereunto set my hand in the presence of two subscribing witnesses.

LEWIS E. GOULD.
